UNITED STATES PATENT OFFICE.

HUGO LENTZ, OF HALENSEE, NEAR BERLIN, GERMANY, AND CHARLES BELLENS, OF NEUILLY-SUR-SEINE, FRANCE.

SHIFTING ECCENTRIC.

No. 883,031.

Specification of Letters Patent. Patented March 24, 1908.

Application filed April 28, 1906. Serial No. 314,125.

To all whom it may concern:

Be it known that we, HUGO LENTZ, a subject of the German Empire, and resident of 123 Kurfürstendamm, Halensee, near Berlin, 5 in the Empire of Germany, engineer, and CHARLES BELLENS, a subject of the Kingdom of Great Britain, residing 43 Rue de Chézy, Neuilly-sur-Seine, in the Republic of France, have invented certain new and useful Im- 10 provements in Shifting Eccentrics, of which the following is a specification.

This invention has for its object a means for effecting the displacement of machine parts by the direct contact of members ap- 15 propriately toothed or screw threaded. It is known that when two racks with teeth ar- ranged obliquely to their length are in engage- 20 ment, the movement of translation imparted to one of them may be directly transformed into a movement of translation of the other.

The invention consists in the application of this method of transmission for producing a displacement of parts such for example as the sheafs of distributing eccentrics, the 25 frames of machine tools and so forth.

In the accompanying drawings which represent by way of example the application of the invention to steam locomotives; Figure 1 illustrates a plan view of an apparatus 30 mounted upon the counter shaft of a locomotive for producing the change of position of the eccentric sheaf. Fig. 2 is a diagrammatic side elevation of a locomotive showing the application of this type of transmission 35 and its controlling means arranged for the displacement of the distributing eccentric at varying angles. Fig. 3 shows a longitudinal vertical section of the apparatus. Figs. 4 and 5 are cross sections on the lines 4—4 and 40 5—5, respectively, in Fig. 3.

The transmission gear is obtained by mounting upon a common support the part or various parts which are to be displaced, with which support they are in direct engage- 45 ment by means of oblique teeth or ribs; a longitudinal movement of translation is given this support by means of an operating rod or bar displaceable in the direction of its length or rotatable around its axis.

50 In Fig. 2 the application of the invention to a locomotive is illustrated; for this purpose a transmission gear is provided and at an appropriate place directly upon the driving axle or indirectly by connecting it with

this axle and the operating rod which is connected with operating parts within reach of the driver.

1 is the lever of the valve, 2 the eccentric rod, 3 the eccentric and the mechanism as a whole, 4 the reversing rod and 5 the operat- 60 ing lever. The connection between the operating bar 4 and the mechanism for the angular displacement of the eccentric is represented in detail in Fig. 3. The stud 6 of the counter crank 7 carries a sleeve 8 caused 65 to participate in the movement of rotation of the stud 6 by a groove and feather 9. This sleeve 8 is adjusted upon the stud 6 in such a manner as to be capable of sliding in the direction of its length. Its external form cor- 70 responds to a recess of the same form made in the eccentric sheaf 10 which has oblique teeth or ribs in direct engagement with the sleeve 8 by means of corresponding oblique teeth or ribs 11. It terminates in a cylind- 75 rical part 12 in which there is formed circular non-inclined grooves 13 intended for the reception of ribs on a second sleeve 14 which catches sleeve 8 and slides with it along the stud 6. The grooves 13 therefore render the 80 sleeves 8—12 and 14 solid in their longitudinal displacement while at the same time leaving them independent as regards their movements of rotation around the stud 6. The sleeve 14 is provided with oblique teeth 85 or ribs 15 in direct engagement with teeth 16 of similar form upon the reversing bar 4. This mechanism or kinematic combination is surrounded as a whole by a box or casing 17 which serves as a guide and support for it. 90

The operation is as follows—In running, the sleeve 8—12, and the eccentric sheaf 10 participate in the rotation of the stud 6; the sleeve 14 and the casing 17 however do not rotate with the other parts of the mechanism. 95 When the driver displaces the bar 4 longitudinally in either direction the ribs 16 engag- 100 ing the ribs 15 produce a longitudinal dis- placement of the sleeve 14 on the stud 6 in which movement the sleeve 8 participates owing to the non-inclined grooves 13 and ribs 12, said sleeve during this time, continuing to rotate with the stud 6 and the eccentric sheaf. The longitudinal displacement of the sleeve 8—12 causes the eccentric sheaf to 105 slide in its plane by means of the oblique ribs 11, this resulting in an alteration of the distribution in the cylinders and eventually in

the reversal of the running of the engine. As the sleeve 14 does not participate in the movements of rotation of the crank stud 6, it will be understood that the bar 4 is able to 5 assume various inclinations relatively to the eccentric rod 2 without influencing the operation of the mechanism. It follows from this that the operation of the mechanism and consequently that of the valve gear is not influenced by the rise and fall of the frame of the locomotive.

The transmission of the movement between the operating bar 4 and the sleeve instead of being effected by means of a translation of this bar may be produced by giving it a movement of rotation and the sleeve may be acted upon by this bar either directly or by the intermediary of appropriate parts (not shown).

20 On a locomotive, as in Fig. 2, the driver produces the rotation of the operating bar 4 by means of a hand wheel and of a shaft connected to the operating bar 4 by an appropriate bevel gearing, Cardan joint or other 25 suitable means.

In the foregoing description it has been assumed that the mechanism has been mounted upon a counter crank and in line with the motor axle, obviously it might be mounted 30 upon this motor axle itself, between the wheels or outside the wheels and be placed directly upon the axle or indirectly.

The means described considerably simplifies valve gear and in particular reversing 35 gears on locomotives. The mechanism represented in Fig. 3 comprises an almost closed casing or box thereby rendering appropriate lubrication of all the parts possible, particularly the eccentric or eccentrics and also protects the parts from dust or at all events permits of eliminating the dust from them.

The invention is applicable not only to locomotives but also to all engines and in particular to steam engines, locomobiles, hy-

draulic machines, air compressor pumps, gas 45 motors, machine tools and so forth.

Having now particularly described and ascertained the nature of our said invention and in what manner the same is to be performed, we declare that what we claim is:

1. In a shifting eccentric, the combination with a crank stud, of a sleeve rotatable with the stud but not relatively thereto, and adapted to slide longitudinally on the stud, said sleeve being provided with two sets of 55 ribs, one set inclined and the other circular, an eccentric provided internally with inclined grooves meshing with the inclined ribs of the sleeve so as to be displaceable in its plane, a sleeve slidable on the stud but not 60 rotatable therewith, said sleeve being provided with circular grooves meshing with the circular ribs of the first named sleeve, and with inclined ribs, an operating rod having inclined ribs meshing with the inclined ribs of 65 the sleeve, operating levers for displacing the rod, and a casing supporting the eccentric and the whole mechanism.

2. In a shifting eccentric, the combination of a crank stud, a sleeve mounted to slide 70 on and turn with the stud and provided with inclined ribs, an eccentric provided with inclined grooves receiving the ribs of the sleeve, a second sleeve mounted on the crank stud and connected with the first sleeve to 75 slide but not to turn therewith, said second sleeve being provided with inclined ribs, and an operating rod having inclined ribs meshing with the inclined ribs of said second sleeve.

In testimony of which we have hereunto 80 placed our hands and seals at Milan, Italy this twelfth day of April, 1906.

HUGO LENTZ. [L. S.]
CHARLES BELLENS. [L. S.]

In the presence of—

INGBARTO BARLONY,
ERNESTO SANTI.
